UNITED STATES PATENT OFFICE

MAX S. GOLDSMITH, OF CINCINNATI, OHIO, ASSIGNOR TO THE GOLDSMITH METAL LATH COMPANY, OF CINCINNATI, OHIO, A CORPORATION OF OHIO

FLOOR CONSTRUCTION

Application filed June 18, 1926. Serial No. 116,948.

My invention relates to floor constructions, principally concrete floor constructions, wherein various new results are attained by new and novel means.

An object of my invention is to provide a concrete floor that may have concrete ribs, and having a finished ceiling, that may be of plaster, concrete or other material and wherein lath heretofore used to support such finished ceiling is dispensed with.

Another object of my invention is to produce a molded ceiling and concrete floor structure wherein the present expense incident to hanging of lath and the strenuous labor incident to plastering the ceiling may be eliminated.

Another object of my invention is to provide concrete floors and the like wherein the wiring conduits, pipes for other purposes, etc., can be positioned and arranged with a minimum of time and effort and in an expeditious manner.

Another object of my invention is to provide simple and economical means for attaining the stated and other objects.

These and other objects are attained by the means described herein and disclosed in the accompanying drawings, in which:

Fig. 1 is a fragmental perspective, sectional view of a concrete floor construction having embodied therein my invention.

Fig. 2 is a fragmental, perspective, sectional view of a modified form of concrete floor construction embodied therein of my invention.

Fig. 3 is a side elevation of a casing forming a detail of my invention.

Fig. 4 is a top plan view of the casing shown in Fig. 3.

Fig. 5 is a sectional view of a modified form of casing.

Figs. 6 to 10 inclusive are illustrations of devices embodying additional features of my invention.

In its broadest aspect my invention com-

prises any means whereby in a building undergoing construction, an entire ceiling may be molded, and which on solidifying may be bonded, by any agencies or means to a floor capable of formation while in a plastic condition, for example concrete, that is then formed or molded upon or above the ceiling.

In Fig. 1 is shown one form of my invention, wherein a temporary flooring or centering 10 is supported by shoring 11. On the upper surface on the temporary flooring 10 are positioned in spaced relation a number of casings 12 for forming concrete keys 13.

The casings 12 are provided with open ends 14 and 15 and may be given any desired form, for example a truncated cone 16 or a truncated pyramid 17 or the like. Again the casing may take the form of an elongated channel 18 open at its top and extending the length of the floor to be constructed. The

sides of the channel, truncated cone, and truncated pyramid converge upwardly. The casings 16, 17 and 18 may be provided with flanges 19 through which a securing means may pass for securing the casings to the temporary flooring 10. Any other suitable means may be provided for retaining the casing in position. The casings 12 are positioned or spotted, as shown, in longitudinal and lateral alignment having the larger and

contacting the temporary flooring 10. This structure provides a series of pockets having their lower ends sealed by the flooring 10 and upper ends open to receive the plastic concrete. The casings are positioned as shown at Fig. 1, at the lower end of the concrete beams 20. The concrete when poured

enters the open ends 14 of the casing 12 and forms keys integral with the beams 20. After the casings have been positioned a cementitious ceiling material 21, for example plaster, concrete, gypsum composition, etc., is poured on the upper surface of the flooring 10 and around the outside of the casings 12. This substance 21 becomes the finished

ceiling of the room below. After this first cementitious layer has set it may be walked upon by the workmen without damage or injury to the ceiling. The temporary centering is retained in position. The workmen 5 may arrange the domes or tiles 22 upon the upper surface 23 of the ceiling 21 between which domes the beams 20 are to be formed. After the domes 22 have been positioned a 10 second layer of cementitious or other material, for example, concrete, for the floor 24, may be poured. Some of the concrete enters 15 the open ends 14 of the casings 12 and forms concrete keys 13 for bonding the ceiling 21 to the floor 24.

The modified structure shown in Fig. 2 dispenses with the reinforcing beams 20 but 20 is laid in the same manner as above described. After the first cementitious slab or ceiling 21 has set the workmen may walk thereon for positioning the reinforcing bars 25, electrical wire conduits 26, waste pipes 27, etc.

In Fig. 5 I have illustrated a modified 25 form of casing having corrugated inclined sides 28 and 29. The corrugated sides afford a greater supporting surface. The cementitious material is adapted to enter the depressions on opposite surfaces of the sides and 30 affords a substantial lock or bond between the cementitious materials and the casing.

It should be noted that lathing is not used 35 for supporting the ceiling 21, although it is readily evident that in some buildings it may be desired to use reinforcing materials, for example, iron bars or bars of steel or other material, fabricated reinforcements in the nature of metallic webbing or metal lath. Further, having the ceiling formed before 40 the temporary flooring is removed dispenses with the time necessary to have plasterers put up a plaster ceiling. With this method of construction the cost is materially reduced because of the materials and labor dispensed with. Workmen may work quickly and 45 without impediment upon the precast ceiling while engaged in positioning the reinforcing bars for the concrete beams and floor slabs, and conduits and pipes for electric wires, 50 water and waste.

The forms disclosed in Figs. 6 to 10 inclusive suggest a few of the possible variations that may be employed. For example, 55 some of the forms may be imbedded or spotted in the plastic ceiling after the ceiling has been poured instead of being mounted on the temporary centering, see Figs. 9 and 10. Other forms may have more point contacts upon the temporary centering, see 60 Fig. 6. Other forms are adapted to contact the lateral edges of the tiles or domes and thereby preclude spreading and collapsing of the tiles, see Figs. 7 and 8. Other domes 65 may be provided with grooves, beads or other indicia for indicating the height or

thickness to which the ceiling slab should be formed, see Fig. 6. In one of the simplest forms of my invention a channel may be embedded in the ceiling slab, the ends of the legs projecting above the ceiling slab and serving to receive between them the edges of the tiles or domes. Many of the enumerated features of the individual forms referred to may be consolidated in a single means or structure.

What I claim is:

1. In a floor and ceiling construction the combination of a concrete floor having concrete beams, a poured in place ceiling slab, hollow elements embedded in the slab and 80 providing downwardly diverging pockets to receive integral concrete keys formed at the base of the beam for supporting the ceiling.

2. In a floor and ceiling construction the combination of a poured in place continuous cementitious ceiling slab, hollow pocket forming elements embedded in the ceiling slab, supporting beams, and keys formed integral with the beams filling the pockets and 85 supporting the ceiling.

3. In a floor and ceiling construction the combination of a cementitious ceiling slab, selectively positionable means for forming dove-tailed openings in the ceiling slab, and a second cementitious slab entering the openings in the ceiling slab and bonding said 90 ceiling slab to the second cementitious slab.

4. In a floor and ceiling construction the combination of a concrete floor, concrete beams formed integral with the floor, a ceiling slab, hollow metallic pocket forming means carried by the ceiling slab, and depending concrete keys formed on the beams entering the pocket forming means and bonding the beams and the ceiling slab.

5. In a floor and ceiling construction the combination of a poured in place cementitious slab providing a finished ceiling face and having pockets formed in its upper face and a cementitious structural floor mass cast 100 upon said upper face of the ceiling and entering the pockets to form integral keys whereby the ceiling is suspended from the floor.

6. A floor and ceiling construction comprising a precast finished ceiling, means in the body of said ceiling providing hollow open topped pockets therein, and a structural cementitious floor cast upon said ceiling and having integral portions thereof filling the pockets in the ceiling to form keys 110 for suspending said ceiling.

7. The method of building comprising erecting a temporary support, placing pocket molding means thereon, casting a continuous cementitious slab on the support and around the pocket forming means to provide hollow pockets in the slab, allowing said cast cementitious slab to harden, then casting a second structural cementitious slab 115 120 125 130

over the first slab and filling the pockets in the first slab, then allowing the second slab to set and removing the temporary support.

8. The process of building construction comprising pouring a cementitious ceiling slab with a finished lower face and provided with openings in its top face, permitting said slab to harden, forming a cementitious structural floor slab over the ceiling slab and filling the openings in the ceiling with the material of the floor slab to bond the ceiling to the floor.

In testimony whereof, I have hereunto subscribed my name this 16th day of June, 1926.

MAX S. GOLDSMITH.
